19 CLARENCE L. DEWEY
by Irene Rain Kinkley

UNITED STATES PATENT OFFICE.

CLARENCE L. DEWEY, OF ELKHART, INDIANA.

DECOY.

Application filed February 29, 1924. Serial No. 696,056.

To all whom it may concern:

Be it known that I, CLARENCE L. DEWEY, a citizen of the United States, residing at Elkhart, in the county of Elkhart and State 5 of Indiana, have invented certain new and useful Improvements in Decoys, of which the following is a specification.

The invention relates to improvements in decoys, and has especial reference to decoys 10 for enticing swimming birds or fowls.

One of the objects of the invention is to provide a life-like decoy when viewed from any angle above the decoy.

Another object is to cheapen the construction 15 of such devices and to arrange the parts thereof so that they may be packed in a relatively small compass.

A further object is to provide improved means for assembling the parts of the structure and for holding them together.

A further object is to provide a base composed of two members each of which is of substantially the same appearance and profile as the vertically disposed member to be 25 supported thereon and therebetween.

There are other objects and advantages which will readily appear from a consideration of the following description when taken in conjunction with the drawing, wherein:—

Fig. 1 shows a side elevation of the device simulating the appearance of a duck.

Fig. 2 is a top plan view of the device.

Fig. 3 is the vertical profile plate.

Fig. 4 is a horizontal profile buoyant 35 plate made up of two parts of equal size.

Fig. 5 is a side view on line 5—5 of Fig. 4.

In all of the views the same reference characters are used to indicate corresponding parts.

The decoy is made of three major portions. The base is provided by the buoyant members 40 10 and 11, which may be of wood having a suitable water proofing coating to prevent them from being water-logged.

These two members when joined together as shown in Fig. 4 have the outline of a duck 45 when viewed from above. They are painted to harmonize in color and character with the profile member 12 which is to be imposed be-

tween the members 10 and 11 and positioned 50 at right angles thereto.

The members 10 and 11 are held together by relatively thin metal plate 13 which is painted so as to render its outlines substantially invisible.

A relatively narrow space 14 is left between the members at the fore end and a wider space 15 at the rear end.

When assembling the members for use, the member 12 is placed in the space or slot 14 and moved rearwardly when the plate 13 will enter the slot 16 in the member 12. By the joint thus made and by the members 10 and 11 on each side of the slot 14, the member 12 is retained in place and held in an upright position. The member 12 has a perforation 17 thru which a latch wire 18 passes to lock the member 12 and prevent its removal until unlocked by removal of the wire.

A ballast rod 19 swings on a pivot 20 and is normally contained in the slot 15, and has its free end turned back upon itself at 21 to increase its weight without increasing its length. The ballast rod is also locked in vertical extended position by the latch wire 18, as clearly shown.

The member 12 has a perforation 22 thru which to pass a cord 23 to anchor the device by the weight 24.

To pack the device for shipment, the member 12 is unlatched and removed; the rod 19 is raised to its position between the members 10 and 11 and the member 12 is placed flat over the members 10 and 11, thus economizing space and making a compact package.

The parts may quickly be assembled and knocked down and packed.

Having described my invention what I 90 claim as new and desire to secure by Letters Patent, is:—

A decoy simulating a swimming bird, comprising two like buoyant members spaced apart to provide an open slot therebetween; a plate overlying said members bridging the slot and secured to both members to hold them in spaced relation; a rela-

tively thin member vertical to the buoyant members having a slot in its rear end to receive said plate when said members is slid into position between the separated buoyant members; a ballast rod, normally retained in said slot between the buoyant members and pivoted at one end thereto near the longitudinal center thereof and arranged

to swing on said pivot into a position vertical to said buoyant members and a latch 10 to hold said rod and said vertical member in place.

In testimony whereof I hereunto set my hand.

CLARENCE L. DEWEY.
